UNITED STATES PATENT OFFICE

2,384,656

SANDING DEVICE

George W. Thomas, Athens, Ga.

Application March 21, 1945, Serial No. 583,941

1 Claim. (Cl. 51—190)

This invention relates to a flexible sander, and more particularly to such a sander of the rotary power-driven type.

A primary object of this invention is the provision of an improved sander of the rotary type characterized by an underlying layer of flexible or resilient material surrounding a power-driven drum, whereby flexibility is imparted to the sandpaper or emery cloth surrounding the reel to provide an improved and enhanced smoothness in the sanded work.

A further and more specific object of the invention is the provision of means adapted to be positioned under the emery cloth or the like and overlying the inner flexible roll, which will serve as a guard to preclude the sandpaper or emery cloth from becoming disengaged from the underlying roll.

A still further object of the invention is the provision of such a device wherein the interior arrangement is such as to preclude the possibility of ingress of dust or sawdust occasioned by the sandpaper or the like to the interior of the sanding drum or head, whereby to prevent clogging thereof.

Still another object is the provision of such a device wherein the inherent flexibility of the sanding drum or head is such that virtually no dust accumulates on the felt or on the sandpaper on the exterior of the device.

A further object is the provision of such a device which may be readily driven by a flexible shaft or the like, in order to provide even more flexible operation thereof to provide access to places which otherwise would be difficult or impossible to sand.

A still further object is the provision of such a device which will be sturdy and durable in construction, reliable and efficient in operation, and relatively simple and inexpensive to manufacture, assemble, and operate.

Other objects reside in the combinations of elements, arrangements of parts, and features of construction, all as will be more fully pointed out hereinafter and shown in the accompanying drawing, wherein there is disclosed a preferred embodiment of this inventive concept.

In the drawing:

Figure 1 is a side elevational view of the sanding device of the instant invention shown in association with a driving chuck therefor, certain concealed parts thereof being shown in dotted lines.

Figure 2 is an end elevational view of the

device shown in Figure 1, as viewed from the right.

Figure 3 is an enlarged longitudinal sectional view taken substantially along the center line of the device.

Figure 4 is a sectional view taken along the line 4—4 of Figure 3 as viewed in the direction indicated by the arrows.

Figure 5 is a sectional view taken substantially along the line 5—5 of Figure 4, as viewed in the direction indicated by the arrows, certain parts thereof being omitted, and

Figure 6 is an enlarged perspective view of a constructional detail.

Similar reference characters refer to similar parts throughout the several views of the drawing.

Having reference now to the drawing, there is generally indicated at 10 the device of the instant invention, which is provided with a driving shank 11, secured thereto in a manner to be more fully described hereinafter, one end of which is adapted to be secured for rotation in a chuck 12 of any conventional design. The chuck 12 may be rotated by a conventional hand motor 13 or the like, or may be driven through a flexible shaft of any desired known type.

The sanding head 10 is comprised of a central core or drum 14, into and beyond the center of which extends a slot or recess 15, intersected by a bore 16. The drive shank 11 is reduced, as at 17, and terminates in a threaded portion 18, the reduced portion being adapted to be passed through the bore 16 and the threaded portion to extend into the slot 15. A nut 19 and washer 20 hold the shank and the core member 14 securely in related assembly, access being had to the nut by means of the slot 15.

A tubular sleeve 21, preferably comprised of felt or similar material, is positioned about the drum 14, and is held in position, as by means of clips or clamps 22, one of which is provided with a cut-away portion 23 permitting it to pass about the shank 11, and which clips are in turn secured in position, as by end plates 24 and 24', the latter being provided with a central aperture to permit the passage of the driving shank 11 therethrough.

Plates 24 and 24', and correspondingly clips 21, are held in related assembly, as by means of bolts 25 passing through suitable bores in the central core 14, and engaging interiorly threaded sleeves 26, passed into the bores from the opposite extremity of the device.

Surrounding the felt sleeve 21 is the strip 30

of cardboard or similar material, which terminates, as indicated at 31, just short of the extremities of the sleeve 21. Adapted to be positioned around the exterior of the entire device is a layer of abrasive material 32, of any desired type dependent upon different kinds of work for which the device is employed. Such material may be sandpaper, emery cloth, emery paper, granite paper, or any other suitable material, a variety of sleeves being readily interchangeable by merely sliding the abrasive material on and off the interior cardboard member 30. The cut-away extremities 31 of the cardboard permit the edges of the abrasive material to engage with the felt, and accordingly preclude slippage of such material from the sander.

Now, from the foregoing, it will be seen that there is herein provided an improved flexible sander accomplishing all the objects of this invention, and others, including many advantages of great practical utility and commercial importance.

As many embodiments may be made of this inventive concept, and as many modifications may be made in the embodiment hereinbefore shown and described, it is to be understood that

all matter herein is to be interpreted merely as illustrative and not in a limiting sense.

I claim:

5 In a device of the character described, in combination, a cylindrical core having a centrally disposed bore therein opening into a recess, said core also having a plurality of additional bores spaced from said central bore extending therethrough, a shank extending through said first-
10 mentioned bore and having a threaded extremity extending into said recess, a nut engaging said extremity, a sleeve of relatively soft material surrounding said core, a sheet of cardboard surrounding said core, a sheet of abrasive material positioned about said cardboard, cover plates overlying said core at its extremities, clips beneath said plates to hold said sleeve in related assembly, one of said plates having an aperture therethrough to accommodate said shank, both
15 of said plates having spaced peripheral apertures therein in alignment with said second-mentioned bores in said core, and bolts passed into said last-mentioned apertures and bores to hold said plates, core and sleeve in related assembly.
